UNITED STATES PATENT OFFICE.

GEORGE A. MARSH, OF NORFOLK, VIRGINIA, ASSIGNOR TO SPECIALTY MANUFACTURING-SALES CORPORATION, OF NORFOLK, VIRGINIA, A CORPORATION OF VIRGINIA.

LANTERN.

1,194,307.

Specification of Letters Patent. Patented Aug. 8, 1916.

Application filed December 10, 1915. Serial No. 66,151.

To all whom it may concern:

Be it known that I, GEORGE A. MARSH, a citizen of the United States, residing at Norfolk, in the county of Norfolk and State 5 of Virginia, have invented certain new and useful Improvements in Lanterns; and I do hereby declare the following to be a full, clear, and exact description of the same, reference being had to the accompanying 10 drawings, forming part of this specification.

This invention relates to improvements in lanterns and more especially to that type of lantern wherein means is provided for producing a different colored light, for instance, a white or a red light, for use in 15 signaling.

The invention consists in certain novel details of construction and arrangements and combinations of parts all as will be now described and particularly pointed out in the appended claims.

Referring to the accompanying drawings.—Figure 1 is a side elevation, partly in section, of the lantern. Fig. 2 is a top plan view, omitting the top, the guard and the globe. Fig. 3 is a section on the line 3—3 of Fig. 2, looking in the direction of the arrow. Fig. 4 is a bottom plan view. Fig. 5 is a sectional view on the line 5—5 of Fig. 4, looking in the direction of the arrow. Fig. 6 is a detail view of the wick actuating means. Fig. 7 is a detail view of one of the hooks for holding the shield in its lower position. Figs. 8 and 9 are detail views of the shield.

Like reference characters throughout the several figures indicate the same parts.

In the drawings, 1 represents the body portion of the lantern having the ventilating perforations 2 therein and the ordinary globe 3 and wire guard cage 4, all mounted on the body portion in the usual manner. The base 5 of the lantern is detachably secured to the body by spring latch 6 (Fig. 2) and is provided with apertures 7, 7, 8, 8, 9, 9, 45 and 10 (Fig. 4) for a purpose presently to be described. Secured to the base 5 are a plurality of upwardly extending rods 11 (Figs. 1 and 3) preferably connected at the upper ends by an annulus 12, the connections at the ends of the rods being preferably formed by nuts 12^a, as shown. Mounted to slide on the rods between the base and annulus is a shield 13, preferably a cylinder of translucent material, suitably colored, said 55 cylinder being formed of two semi-cylindri-

cal sections, retained between spaced annuli 14, 14^a having shield retaining lugs 15. The annuli 14, 14^a are of greater breadth than the thickness of the cylinder to form inwardly extending flanges, to the lower one 60 of which upwardly extending rods 16 are secured, in any suitable manner. Rods 16 are of a greater length than the height of the cylinder and extend upwardly through annulus 14^a, said rods being provided at 65 their upper ends with enlargements 16^a, usually formed by nuts 16^b. To facilitate the removal and replacement of the sections because of breakage, or when it is desired to clean the shield, springs 17 are mounted 70 on rods 16 between the enlargements 16^a and the upper annulus. Normally, springs 17 tend to press the annulus 14^a downwardly so that the lugs 15 engage the outer surface of the sections, but by elevating annulus 14^a a 75 sufficient distance as to raise the lugs 15 thereof above the top of the cylinder or shade, any or all of the sections may be readily removed from between the annuli. Said inwardly extending flanges formed by 80 annuli 14, 14^a are also provided with apertures for rods 11 whereby the shield 13 is guided and permitted a vertically sliding movement. A cushioning effect is obtained between the glass cylinder and annuli 14, 14^a 85 by inserting between the ends of the cylinder and each annulus an asbestos gasket 18. An elevating spring is provided for the shield, said spring preferably taking the form of a large spiral spring 19 interposed 90 between the base 5 of the lantern and the lower annulus 14 of the shield, said spring, when released, being adapted to raise the shield to a point opposite the flame of the lantern. Mounted on each of the rods 11, 95 intermediate the upper annulus 14^a of the shield and the annulus 12 is a spiral spring 20, these springs being adapted to absorb the blow of the shield when said shield is elevated by the spring 19. 100

To hold the shield below the flame against the tension of spring 19, the inwardly extending flange, formed by the bottom annulus 14 of the shield, is provided with two downwardly-projecting hook-shaped members 21, which, when the shield is in its lowered position extend through apertures 7, 7, in the base and are engaged by a latch 22, pivotally mounted on the under side of the base 5 preferably on a central rivet 23. 110

Latch 22 is normally held in position to engage the hooks 21 by a spring 24 interposed between a downwardly extending projection 22^a on one end of said latch and a projection 25 struck up from the base of the lantern.

For depressing the shield below the level of the flame a yoke, consisting of side members 26, 26, connected at their lower ends 10 by a cross bar 27, is slidably mounted in the base of the lantern (Figs. 3 and 4) and loosely connected within the shield. The cross bar 27 is located below the base and is normally held up by a spring latch 28 extending upwardly from the crossbar through one of the apertures 8 in position to engage the upper side of the base. The side members 26 extend from the cross bar upwardly through apertures 8, 8, in the base and also 20 through apertures 18^a in the lower flange or annulus 14 of the shield. At their upper ends they are enlarged as at 29 forming heads larger than the diameter of the openings in the annulus 14 through which the 25 side members pass. When the latch 28 is unlocked, the shield may be drawn down against the tension of the spring through the medium of the cross bar 27. The shield is lowered until the hooks 21 are engaged 30 by latch 22, when it is thus locked in its lower position, and the yoke can then be pushed upwardly to its normal position, independently of the shield, and held in that position by the latch 28.

When in its lower position (Figs. 1 and 3) the shield is below the burner so that when lighted the lantern will display a white light, but when elevated the shield surrounds or envelops the flame, when the lantern will display a red or other colored light, according to the color of the shield. Mounted on the base within the shield is an oil pot 30, carrying the wick holder and burner 36, the oil pot preferably being 40 movably secured to the base by screws 31 passing through openings 9, 9 in the base, and the heads of the screws being engaged on the under side of the base by a latch 33 pivotally mounted on rivet 23 (Fig. 4). A tube 34 mounted in the oil pot extends below the base of the lantern through the aperture 10 and upwardly to a point in the top of the oil pot adjacent a gear wheel 35 which latter is adapted to raise or lower a 55 wick in the burner 36 in the usual manner. In lanterns of this type it is desirable that means be provided for adjusting the wick without the necessity of raising the globe, and for actuating the wheel 35 from the exterior, without raising the globe, a bar 37, provided at its upper end with teeth 38, adapted to engage wheel 35, extends upwardly through tube 34 to the wheel 35. Bar 37 is provided, on one of its edges at a 60 point intermediate its ends, with a curved 65 point intermediate its ends, with a curved

projection 39, this projection being adapted to abut against the wall of tube 34 to form a pivot upon which the bar may be swung in a vertical plane to throw the teeth 38 on its upper end into and out of engagement 70 with the gear wheel 35. When the teeth 38 and wheel 35 are in engagement the wick may be raised or lowered by an upward or downward movement of bar 37 and when said teeth and wheel are out of engagement 75 with one another the bar 37 is prevented from falling out of the tube by a pin 40 which projects from one side of the bar and engages the top of the oil pot. The bar also has its lower end below the base of the lantern bent to form a finger piece 41 by which it may be operated in a convenient manner.

What is claimed is:

1. In a lantern, the combination with the base having a plurality of upwardly extending rods mounted thereon, of a shield mounted to slide on said rods whereby it may be raised and lowered and having downwardly extending hooks at its lower end, a yoke slidably mounted in the base having means for 85 lowering the shield, and a locking member mounted on the base in position to engage said hooks and hold the shield in its lower position independently of the yoke.

2. In a lantern, the combination with the 90 base having a plurality of upright rods mounted thereon, of a shield having annuli forming flanges thereon provided with apertures for said rods, said shield being slidable in a vertical plane on said rods, downwardly 100 projecting hooks on one of the annuli, a yoke slidably mounted in the base and co-operating with one of said annuli when the shield and yoke are in their upper positions whereby said shield may be lowered by a downward movement of the yoke, and a latch mounted on the base and engaging said hooks when the shield is in its lowered position to retain the shield whereby the yoke may be returned to its upper position independently of the shield.

3. In a lantern, the combination with the base having a plurality of slots therein, of a shield having annuli forming flanges thereon, upwardly extending rods on the base extending loosely through the annuli, said shield being adapted to be raised and lowered on said rods, downwardly projecting hooks on one of said annuli, a yoke slidably mounted in the slots in the base and having 115 the upper ends of its side portions enlarged, said enlarged ends being extended above and in loose engagement with one of the annuli whereby the shield may be depressed by a downward movement of the yoke, and a latch 120 mounted on the base to engage the hooks and hold said shield in its lower position, whereby the shield is held in its lower position independently of the yoke.

4. In a lantern the combination with the 130

- base, of a shield having annuli forming flanges at its upper and lower ends, upwardly extending rods mounted on the base and extending through the annuli on the 5 shield, said shield being adapted to be raised and lowered on said rods, hooks on the lower annulus and projecting downwardly therefrom, a yoke slidably mounted in the base and shield and in loose engagement with the 10 lower annulus of the shield for depressing the shield by a downward movement of the yoke, a latch mounted on the base for engaging said hooks when the shield is lowered and holding it in its lowered position independently 15 of the yoke whereby said yoke may be raised upwardly independently of the shield, and a latch on the yoke adapted to engage the base and hold said yoke in its raised position.
- 20 5. In a lantern, the combination with the base having an aperture therein, of an oil pot mounted thereon, a wick actuating gear wheel mounted on the top of the oil pot and adapted to actuate the wick when revolved, 25 a tube extending vertically through the oil pot and having one of its terminals adjacent said gear wheel, a bar extending from below the base through the aperture and tube, rack teeth on the upper end of said bar, 30 and an offset on one edge of said bar adapted to abut against the wall of the tube and form a pivot upon which the bar may be turned in a vertical plane, whereby the upper end of the bar may be thrown into engagement 35 with the gear wheel and said wheel revolved by a vertical movement of the bar.
6. In a lantern, the combination with the base, of an oil pot mounted thereon, a tube extending vertically through the oil pot, a 40 wick adjusting gear wheel mounted on said oil pot, a bar extending through the tube, teeth on the upper end of the bar adapted to coöperate with the gear wheel whereby said wheel may be revolved by a vertical movement of the bar, said bar being adapted to 45 be swung in a vertical plane in said tube, whereby its toothed end may be moved into and out of engagement with the gear wheel.
7. In a lantern, the combination with the base having a plurality of upwardly extending rods mounted thereon, of a shield slideable vertically on said rods, said shield embodying upper and lower annuli, a sectional shade retained between said annuli and rods connected at their lower end to the lower 50 annulus and extending upwardly through the upper annulus, the upper annulus being slideable vertically on said rods independently of the lower annulus to permit the removal of the shade sections. 60
8. In a lantern, the combination with the base having a plurality of vertically extending rods mounted thereon, of a shield mounted to slide vertically thereon, said shield embodying spaced annuli, projections on said 65 annuli extending toward each other, a sectional shade removably retained between said annuli by said projections, rods connected at their lower ends to one of said annuli, and extending upwardly through the 70 other of said annuli, enlargements on the upper end of said last mentioned rods and springs mounted on said rods between the enlargements and adjacent annulus adapted to hold said adjacent annulus against the 75 shield sections, said last mentioned annulus being slideable vertically on said rods with respect to the other annulus, whereby the sections of the shade may be removed from between the annuli.

GEORGE A. MARSH.
